NURSING BOTTLE

Michael C. Ritsi, 7950 SW. 16th St.,
Miami, Fla. 33145

Filed Aug. 29, 1968, Ser. No. 13,311

Term of patent 14 years

Int. Cl. D24—05

U.S. Cl. D83—8

FIG. 1 is a front elevational view of a nursing bottle showing my new design;

FIG. 2 is a bottom plan view; and

FIG. 3 is a top plan view thereof.

I claim:

The ornamental design for a nursing bottle, as shown and described.
